POTATO STAMPING MACHINE
Glen W. Mallory, American Falls, Idaho, assignor to
Robert C. Weaver, Declo, Idaho
Filed Dec. 28, 1965, Ser. No. 516,987
4 Claims. (Cl. 101—35)

This invention relates to machines for stamping an identifying mark on the skins of regular or irregular shaped vegetables, and fruits, and is particularly concerned with such machines used to mark potatoes.

In the past there have been many attempts made to mark potatoes so that consumers will be able to identify them as being produced in a certain geographical area, or by a particular grower, etc. These attempts have generally been directed toward stamping the potato with special inks, but, while being somewhat successful, they have not overcome all of the problems encountered. Ink applied to a potato is easily rubbed off during handling and will not withstand the thorough scrubbing usually given the potato before it is baked, or otherwise prepared for consumption with the skin intact. Thus, the ultimate consumer (a customer in a restaurant, for example) may not be assured of the quality of the potato he receives, even though he desires and specifies a particular potato.

Ink stamps cannot be used to mark wet potatoes and since they are usually washed shortly after being taken from the field, potatoes generally cannot be marked with an ink stamp until they have been allowed to dry naturally or until they have passed through a drying machine. In either case, there is an unnecessary time and expense involved. The inks used in such operations must be specially formulated so as not to contaminate the potato, and if a stamping head fails to contact the potato it is re-inked and a double charge of ink smears on the next potato to be contacted.

Principal objects of the present invention are to mark potatoes, whether they are wet or dry, clearly and distinctly and in such a manner that the mark will not wash off during normal scrubbings, or be wiped or worn off during normal handling.

Outstanding features of my invention include closely spaced, small, heated stamping heads that effectively brand potatoes of widely varying sizes. A spring biased continuous chain pressure applier guides the potatoes and insures that they are lightly pressed into contact with the stamping heads. A circulating coolant maintains the components of the hub on which the heads are mounted, except for the heads themselves, cooled, so that only the portion of the potato contacted by the stamp is subjected to heat application. The light pressure applied during the branding results in only the skin being scored and the intense heat applied effectively cauterizes the vegetable to prevent spoilage starting at the brand.

Although here disclosed as being particularly useful in marking potatoes, it has been found that other fruits and vegetables can be similarly marked. For example, oranges, lemons, and onions all have been successfully branded.

There is shown in the accompanying drawings a specific embodiment of the invention representing what is presently regarded as the best mode of carrying out the generic concepts in actual practice. From the detailed description of this presently preferred form of the invention, other more specific objects and features will become apparent.

In the drawings:

FIG. 1 is a top plan view of the potato stamping machine of the invention;

FIG. 2, an elevation view of one side of the machine;

2

FIG. 3, a view in elevation of the opposite side;

FIG. 4, an enlarged, fragmentary horizontal section taken on the line 4—4 of FIG. 2 and showing the hub arrangement;

FIG. 5, an enlarged vertical section taken on the line 5—5 of FIG. 1;

FIG. 6, a vertical section through the hub, taken on the line 6—6 of FIG. 5;

FIG. 7, a still further enlarged, fragmentary vertical section taken on the line 7—7 of FIGS. 4 and 6;

FIG. 8, an enlarged, and exploded view, in perspective, of the hub shaft and electrical slip rings; and

FIG. 9, an enlarged perspective view of a stamping head.

Referring now to the drawings:

In the illustrated preferred embodiment the potato stamping machine of the invention, shown generally at 20, includes a frame that supports a rotatable stamping hub 21, a special feed belt 22, the drive motor 23 for the hub and the belt, and pressure applicator chains 24, that hold potatoes firmly against the hub during stamping operations.

The frame includes corner legs 25, 26, 27, and 28, rigidly interconnected by lower side members 29, upper side members 30, and end members 31.

The special endless feed belt 22, at one of its ends, passes around sprockets 32 mounted on a shaft 33 that is journaled in bearings 34 within blocks 35 carried by the upper side members 30. The other end of belt 22 passes around sprockets 36 that are mounted on a shaft 37, journaled within bearings 38 in posts 39 that interconnect the lower and upper side members 29 and 31 and form part of the frame of the machine.

The special endless feed belt is made up of interconnected rods 40 that are curved intermediate their lengths to provide a series of dwells 40a. At their ends the rods are each bent slightly with respect to their elongate axes and with the bent ends then being formed into hooks 40b that link with the rod ahead to form an endless belt in which the dwells of the rods are aligned so as to form continuous guide gutters in advance of the stamping hub. The rods intermesh with the teeth on sprockets 32 and 36 as the belt is driven.

Potatoes are fed into each of the guide gutters formed by the aligned dwells 40a from a separator unit that is not shown, but that can be of any conventional kind, and are then carried by the rods 40 to stamping hub 21. Because of the curved shape of the dwells the potatoes are held in alignment with the stamping hub such that the potatoes in each gutter will discharge onto a row of stamping heads 41 that extend around the hub. To further center each potato with respect to its proper row of stamping heads, a pair of spring strips or fingers 42 and 43 are positioned such that the potatoes in each gutter must pass between them. Each of the spring strips has one end fixed to a rod 44 extending between opposite sides of the frame and positioned far enough above the feed belt that the potatoes can easily pass therebeneath and the other end of each strip extends downwardly beyond the discharge end of the endless belt 22 and toward the other of the spring strips making up the pair. With this arrangement any size potato will enter the opening between the pair of spring strips, even if the potato is not precisely centered in the associated gutter.

As the potato passes between the converging strips it is forced to a center position and is aligned to be properly discharged over a rotating rod 45 and onto a row of stamping heads 41 on the hub 21.

Hub 21 is made up of a hollow central shaft 47 having rings of radiating spokes 48 spaced along its axis to

serve as supports for guides 49 that provide outer rims for the hub.

The guides are hollow so that, as will be further explained, coolant water can be circulated through them. They each have a flat base surface 50, welded or otherwise fixed to their respective ring of spokes, and a curved outer surface 51 that extends from a central outer apex symmetrically in a reversing curve such that any size potato will fit snugly between adjacent guides.

A pair of generally ring-shaped heating elements 52 and 53 are positioned between the base surfaces 50 of the guides and are held in position by spaced retainers 54, extending between the guides inside of the circle formed by the heating elements. Retainers 54 are removably connected to the guides by nuts 55 that hold the retainers on threaded stub posts 56. Terminal posts 57 and 58 are formed at the ends of each of the heating elements and a lead wire 59 interconnects each terminal post 57 with a main line 60 extending axially along central shaft 47 and a similar lead wire 61 interconnects each terminal post 58 with the other main line 62 extending axially along central shaft 49.

The heating elements are thus each connected in parallel and are easily disconnected from their heating circuit for replacement should they become defective.

Power is supplied main lines 60 and 62 through slip rings 63 and 64 that are contacted by brushes 65 and 66 at the ends of lines 60 and 62, respectively. The slip rings are on the inside of sleeve 67 and terminal posts 68 and 69 extend through the sleeve from slip rings 63 and 64, respectively, to be connected to any conventional power source, not shown.

Stamping heads 41, FIG. 9, are each formed with an upstanding central portion 70 which includes the raised lettering or design making up the mark to be stamped, and an enlarged base 71. The stamping heads are spaced around each pair of ring-shaped heating elements such that at least one head will come in contact with each potato moved onto the hub, and with their bases each resting on the heating elements, making up a pair. The stamping heads are made of a long wearing material having good heat transfer characteristics, and a brass alloy has been found satisfactory for this purpose.

A band 72, preferably made of a good thermal conductor such as copper, has spaced holes therein through which the upstanding central portions 70 of the stamping heads protrude and the band is affixed tightly to hub 21 by means of screws 73 that extend through the band and into retainers 54 between the stamping heads. Since the band 72 rests on each of the bases 71 the stamping heads are held in their set position. Should the heads need to be replaced they are easily accessible upon removal of band 72.

As potatoes are moved onto the stamping head they are pressed against one or more of the stamping heads by the pressure applicator chains 24 and are carried with the hub until they pass beneath the pressure applicator chains and are discharged to a chute 74. If desired a conventional belt conveyor (not shown) can be used instead of the chute to transport branded potatoes from the stamping hub.

A pair of the endless pressure applicator chains 24 are arranged to pass above each row of stamping heads 21 and around sprockets 75 that are fixed to a shaft 76 and sprockets 77 fixed to a shaft 78. The chains are aligned such that they pass parallel to the center line of the rows of stamping heads, with one chain at each side thereof.

Shaft 76 is journaled in blocks 79 carried by the upper side members 30 and shaft 77 is similarly journaled in blocks 80 provided for the purpose and carried by extensions 81 that are fixed to corner posts 26 and 28 of the frame.

A flanged roller 82 is adapted to rest on each chain and to hold it in position to contact a potato moved onto

the associated row of stamping heads. The rollers are each carried by the free end of a pivot arm 83 that is mounted for swinging through a vertical arc on a shaft 84 carried by brackets 85 that are fixed to upright posts 86 forming a part of the machine frame. The amount of pressure applied to the pressure applicator chains, and therefore to the potatoes passing beneath can be varied, as desired, merely by sliding a weight 87 along the arm 83 to change the moment force at the point of contact between the roller and the chain. Because of the off-centered positioning of the chains of each pair, with respect to the stamping heads, they will contact each potato at at least two points to press it firmly against the stamping head, and, since the rollers 82 are each yieldably mounted the chains can individually conform to the size and shape of the potato passing therebeneath.

A hollow rod 88 is journaled through plates 89 and 90 at opposite sides of the frame to assist the potatoes in moving from the feed belt 22 onto the stamping hub 21.

Stamping hub 21, feed belt 22, pressure applicator chains 24, and hollow rod 88 are all driven from the same motor 23. Thus, a drive belt 91, FIG. 3, passes around a pulley 92 driven by the motor and a large pulley 93 connected to one end of stamping hub 21. Another drive belt 94 passes around a pulley 95 fixed to the other end of hub 21, a pulley 96 on the end of shaft 33, hollow rod 88 and guide pulleys 97 and 98, on the frame. Clockwise rotation of pulley 92, as viewed in FIG. 3, results in rotation of the stamping hub in the direction of the arrows shown therein and a simultaneous rotation of pulley 96, shaft 33, the sprockets 32, the feed belt 22, and hollow rod 88 in the directions indicated by the arrows adjacent thereto.

At the same time a pulley 99 on the end of shaft 76 is rotated to drive the pressure applicator chains, as indicated by the adjacent arrows, through a belt 100 that is twisted and passes around another pulley 101 on the end of shaft 33 and an adjustable tension pulley 102. The portion of the pressure applicator chains that contact the potatoes thus move in the same direction of travel as the potatoes being marked.

To prevent the potatoes being damaged as a result of their being heated by structure other than the stamping heads 21, the guides 49 and the hollow rod 88 have water, or other coolant, circulated through them. The water to the guides is supplied through a main supply hose 103 and a branch supply hose 104 supplies water to rod 88. The water runs through the rod and is discharged to waste through a discharge branch hose 105 and a main discharge hose 106. Conventional slip couplings 107 and 108 are provided as connectors between the hoses and rod 88 so that the rod can freely rotate as it assists in moving potatoes from feed belt 22 to the stamping hub 21.

The water circulated through the stamping hub 21 enters hollow central shaft 47 from main supply hose 103 through a conventional slip coupling 109 and is discharged from the central shaft through another conventional slip coupling 110 and main discharge hose 106.

As it enters central shaft 47 the water is diverted by a plug 111 into a bore 112 that extends from the interior of central shaft 47, through a spoke 48, to the interior of the guide 49 nearest the end of the stamping hub to which the water is supplied. The water passes around the inside of the hollow guide until it is diverted by a dam 113 into a connector tube 114 that carries it to the next adjacent guide. Again the water passes around the inside of the guide until it is diverted by a dam 113 into another connector tube 114. This continues until the water has passed through each of the intermediate hollow guides and it has been directed into the last guide at the side of the stamping hub from which the water is discharged. After passing around the inside of this last guide the water is diverted by a dam 115 into a tube 116 that carries it back to central shaft 47. A plug 118 therein then diverts the

water to the discharge hose, in the manner previously described.

In operation potatoes are fed into the guide gutters formed on endless feed belt 22 that carries them to the stamping hub 21. The guide gutters roughly align the potatoes with the rows of stamping heads 41, and the spring strips 42 and 43 insure the alignment such that they are centered between adjacent curved surfaces 51 of guides 49 as they move over rod 88 and onto the rows of stamping heads 41. The rotating rod 88, positioned between the feed belt and the stamping hub keeps the potatoes moving and keeps them from piling up at this point. The pressure applicator chains hold the potatoes in contact with the stamping heads, even though they may have an irregular shape and the marked potatoes are discharged onto a chute 120 and directed away from the potato stamping machine.

Whereas there is here illustrated and specifically described a certain preferred construction of apparatus which is presently regarded as the best mode of carrying out the invention, it should be understood that various changes can be made and other constructions adopted without departing from the inventive subject matter particularly pointed out and claimed herebelow.

I claim:

1. A machine for stamping potatoes and the like, comprising
  - a support frame;
  - a circular hub carried by said frame;
  - at least one row of stamping heads extending around and carried by said hub;
  - a row of hollow guides adjacent each side of each row of stamping heads;
  - conduits interconnecting said guides;
  - means for circulating water through said conduits and said guides;
  - means for revolving said hub;
  - means for feeding potatoes onto said hub between adjacent ones of said guides;
  - means for yieldably holding the potatoes against a row of stamping heads; and
  - means for heating said stamping heads.

2. A machine for stamping potatoes and the like, comprising
  - a support frame;
  - a circular hub carried by said frame;
  - at least one row of stamping heads extending around and carried by said hub;

45

a row of guides adjacent each side of each row of stamping heads;

means for revolving said hub;

means for feeding potatoes onto said hub between adjacent ones of said guides;

means for yieldably holding the potatoes against a row of stamping heads, said means including endless chain means comprising a pair of spaced endless chains passing over each row of stamping heads and roller means for independently pressing each of said chains toward its respective row of stamping heads, said roller means including a roller for each chain and a cantilevered weight biasing the roller into engagement with the chain; and

means for heating said stamping heads.

3. A machine for stamping potatoes and the like, comprising

a support frame;

a circular hub carried by said frame;

at least one row of stamping heads extending around and carried by said hub;

a row of guides adjacent each side of each row of stamping heads;

means for revolving said hub;

means for feeding potatoes onto said hub between adjacent ones of said guides;

guide means for the potatoes comprising a pair of spring fingers fixed to the frame and extending above each row of stamping heads, said fingers converging in the direction of travel of the potatoes and toward the centerline of their respective rows of stamping heads.

4. A machine according to claim 3, wherein the means for feeding potatoes onto the hub includes an endless feed belt made up of rods interlocked at their ends and each formed with a dwell for each row of stamping heads, the corresponding dwells of the rods being aligned to provide a continuous guide gutter for each of the stamping heads.
